APPLIANCE FOR STROPPING SAFETY
RAZOR BLADESCharles Klopfenstein and Vernon A. Stewart,
Fort Wayne, Ind.

Application November 27, 1933, Serial No. 699,840

1 Claim. (Cl. 51—153)

This invention relates to improvements in appliances for stropping safety razor blades, one of the objects being to provide a holder for a safety razor blade of either the single or double edged type, and which when applied to a strop and moved to and fro thereon will cause the exposed edge of the razor blade to be stroked angularly upon the strop alternately in opposite directions and correspondingly upon the opposite faces of the blade.

Another object is to construct the holder so that the edge of the razor blade when stroked upon the strop in either direction will be sustained in an oblique position respecting the strop.

15 A further object is to provide in a stropping device a reversible holder for a double-edged razor blade and securing means therefor in selected positions so that either one or the other of the edges of the blade is applied to a complementary strop when the appliance is operated.

20 Other objects and advantages of the invention will appear in the following description.

An illustrative embodiment of the invention is shown in the accompanying drawing, in which:—

25 Fig. 1 is a plan view of a structure in which the invention is embodied;

Fig. 2 is an end elevation of the structure shown in Fig. 1, applied to a razor strop, a fragmentary portion of which is included in the figure;

30 Fig. 3 is a side elevation of the razor blade holder, portions being in section;

Fig. 4 is a plan view projected from Fig. 3, the hinged clasp being omitted;

Fig. 5 is a perspective view of a fastener for 35 securing the blade holder in selected positions in its frame;

Fig. 6 is a perspective view of a bolster for the razor blade holder; and

Fig. 7 is a perspective view of a razor blade 40 illustrating one of a type adapted to the appliance.

The illustrative embodiment of the invention is comprised of a base 1 having a pair of spaced ears 2 extending outwardly from its back and in which 45 is pivotally secured an operating handle 3. The base has at each end a forwardly extending arm 4 and has curved edges 5 that are inclined forwardly and which extend substantially from one end of the base to the opposite end thereof.

50 Between the arms 4 is rotatably mounted a friction roller 6 having end trunnions 7 and 7' that extend loosely through the arms 4, and the trunnion 7' has secured upon its end external of the adjacent arm 4 a spur-gear 8. Also, between the 55 arms 4 is mounted a rock-frame 9 provided with

trunnions 10 and 10' that extend loosely through said arms, and the trunnion 10' has secured thereon a spur-gear 11 that meshes with the aforesaid gear 8 so that upon turning movement of the friction roller 6 upon its axis in either direction corresponding opposite turning movement is thereby imparted to the rock-frame 9.

Upon the ends of the rock-frame 9 are disposed corresponding radially disposed arms 12 and 12', the arm 12 being of greater length than the arm 10 12', and between the arms for the rock-frame is mounted a razor blade holder 13 having at its ends trunnions 14 that extend loosely through the corresponding arms of the frame adjacent the outer ends thereof. Thus, the blade holder is disposed to turn with respect to the frame upon an axis that is oblique to the axis of the trunnions 10 upon which the frame has turning movement.

The holder consists of a plate 15 having an elongated depression 16 made therein for the reception of a bolster 17 that is held in operating position by its downturned ends 18 that project through openings 19 made in the plate 15 respectively at the ends of the depression and bear snugly against adjacent faces of said plate in 25 said openings. Preferably, the bolster is sprung into operating position in the plate, a portion of which becomes clamped between the ends 18 upon insertion of the bolster in the holder. The plate 15 has hinged thereon adjacent one of its 30 ends a clasp 20 consisting of another plate substantially of the same width as the aforesaid plate 15, and which has made therein a depression 21, which when the bolster is in place and the clasp 35 is closed receives the centering lugs 22 that project from the bolster. The outer end of the clasp has a spring tongue 23 that when the clasp is closed projects through an opening 24 made in the plate 15 and snaps into holding connection therewith. The extreme outer end 23' of the 40 tongue 23 is outwardly turned so as to be engaged by a sliding fastener 25 mounted on the arm 12 that is provided with opposed lips 26 between which the corresponding end of the holder plate 15 is secured when the fastener is in locking position. In this manner the holder is secured from turning with respect to the rock-frame and incidentally the clasp is secured in closed position on the holder by said fastener.

50 In operation, an ordinary razor strop 27 is inserted in the appliance so as to extend in front of the ledges 5 and back of the friction roller 6. When the strop is drawn taut it is slightly flexed and bears with more or less force against the ledges and the roller so that when reciprocating

- movement is applied to the base on the strop by manipulating the handle 3 the roller is oscillated upon its axis because of its frictional contact with the strop and consequently the rock-frame is correspondingly oscillated upon its axis through the medium of the spur-gears 8 and 11. A razor blade 28 is inserted in the holder upon the bolster so that the centering lugs 22 project through the openings 29 and is held in place between the plate 15 and the clasp 20 when the clasp is snapped into closed position. The fastener 25 is then slid into engaging position so that the clasp is locked and the holder prevented from relative turning movement in the rock-frame. Thus, one of the edges of the razor blade is sustained in outermost position and is brought into contact with the strop alternately in opposite oblique trailing positions respecting the strop as the appliance is moved to and fro thereon. The holder may be reversed in its position with respect to the rock-frame so that its other edge will then be foremost so as to be applied to the

strop. In this manner the edges of the razor blade are selectively subjected to dressing treatment on the strop without removing the blade from the holder.

We claim:—

In a stropping appliance for safety razor blades applicable to a strop, a base including a handle therefor, provided with inclined ledges oppositely disposed and an extending arm at each end thereof, a rotatable friction roller disposed between said arms adjacent said ledges, a rock-frame pivotally disposed between said arms geared to said friction roller, and provided with parallel arm members of unequal lengths, a razor blade holder disposed pivotally between said members upon an axis oblique to that of said rock-frame, and a fastener adjustably movable on one of said members for securing said holder selectively in relative reverse positions.
